UNITED STATES PATENT OFFICE.

GEORGE STEPHENS, OF LYNN, MASSACHUSETTS, ASSIGNOR TO THE THOMSON-HOUSTON ELECTRIC COMPANY, OF CONNECTICUT.

CONNECTION FOR ARMATURE-CONDUCTORS.

SPECIFICATION forming part of Letters Patent No. 470,217, dated March 8, 1892.

Application filed November 13, 1891. Serial No. 411,792. (No model.)

To all whom it may concern:

Be it known that I, GEORGE STEPHENS, a citizen of the United States, residing at Lynn, in the county of Essex and State of Massachusetts, have invented certain new and useful Improvements in Connections for Armature-Conductors, of which the following is a specification.

This invention relates to improved means for making connections from the armature-conductors to the commutator-segments. Such connections have been made by supplementary strips connected at one end to the armature-conductors and at the other end to the segments. The separate strip is made flexible for convenience and for diminishing the strains and liability to breakage.

My invention consists in means for attaching the strip to the conductors and segments without the use of solder, while insuring permanent and reliable connection.

In the accompanying drawings, Figure 1 is an axial section of a part of an armature, showing my improved connectors. Figs. 2 and 3 are detail views of the armature-conductor connection. Figs. 4, 5, and 6 show modifications thereof. Figs. 7 and 8 are detail views of the segment connection.

The armature-wire A, having been wound around core B, has its insulation removed for a portion of its length. The end of the connection-strip C is likewise bared and placed against the armature-conductor, so as to bring the bared portions in contact. A strip or band D is then placed over the two conductors and the whole clamped against a resisting abutment, which may be the armature-winding itself. By this means a length of contact may be secured equal to the length of the armature-core, the armature-conductor being bared for a single length along the core. The stranded conductor is thus made to surround and effectually contact with the armature-conductor.

The armature-conductor may be continuous, as indicated in Fig. 6, and be bared at successive points corresponding to the last turn of each section where connections from the commutator are to be made. In case the armature-coil sections are separate the adjacent ends of adjoining segments are bared

and placed together and the commutator connection applied, as before. (See Figs. 3 and 4.)

Figs. 2 and 3 show the preferred form of the connection, it being preferably used with a slotted or toothed armature. The coil-sections A having been wound up, their ends are bared, as above described. The flexible commutator connection C, having a number of strands of comparatively fine wire, has its bared end placed against the bare portions of the armature-conductor. The strip D is wound over them all, forming a sleeve, as in Fig. 3, and an insulating plate or follower having been placed over the coil-section the sleeve with its contained terminals is placed thereon and a wedge or plug E is driven in over the sleeve, firmly clamping the same against the follower. The upper end of the slot is made tapering, so as to hold the plug in place. Another follower F, preferably of insulation, may be placed between the plug and the combined terminals, as shown in Fig. 5, to prevent displacement or tearing of the latter when the plug is driven in. The strip D is preferably wound around in a spiral form, as shown in Fig. 3.

At the commutator end of the connecting-strip I employ the connection shown in Figs. 1, 7, and 8, the bared end of the stranded connecting-conductor being inserted in a sleeve or socket G, through which passes a screw H, tapped into the commutator-segment and having a square head h, against which a portion of the socket or sleeve G is struck up, as shown at i, to hold the screw from working out.

What I claim as new, and desire to secure by Letters Patent, is—

1. The combination of the bared portions of the armature-conductor and connecting-conductor, the sleeve around the same, and a clamp supported by the armature and clamping said sleeve.

2. The combination of the bared portions of the armature-conductor and connecting-conductor, the metal sleeve around the same, and a clamp holding said sleeve against a portion of the armature.

3. The combination of the armature-coil section, the bared portions of the armature-conductor and the connecting-conductor, the

- metal sleeve placed over the same, the follower over the coil-section and supporting the sleeve, and the clamping-plug placed over the sleeve.
5. 4. The combination of the armature-core having a tapering slot, the coil-section wound therein, the follower placed on said coil-section, the connecting-conductor, the metal sleeve containing bared portions of the armature and connecting conductors and placed on the follower, and a plug driven into the tapering slot over the sleeve.
10. 5. The combination, with the armature-conductor and the stranded flexible conductor having their ends bared, of the sleeve sur-
- rounding both of such conductors and clamping the strands against and around the armature-conductor.
6. The connector for attaching armature connections to commutator-segments, consisting in a screw tapped into the segment and a metal sleeve on the armature connection held under the head of the screw and having a struck-up portion engaging with such head. 20
- In witness whereof I have hereunto set my hand this 10th day of November, 1891. 25
- GEORGE STEPHENS.
